Primary Examiner — Tamara L Hahn*(74) Attorney, Agent, or Firm* — McCarter & English, LLP**(57) CLAIM**

The ornamental design for a support rail, as shown and described.

DESCRIPTION

FIG. 1 is a perspective view of a support rail;
 FIG. 2 is front elevational view of a support rail;
 FIG. 3 is a rear elevational view of a support rail;
 FIG. 4 is a left side elevational view of a support rail;
 FIG. 5 is a right side elevational view of a support rail;
 FIG. 6 is a top plan view of a support rail; and,
 FIG. 7 is a bottom plan view of a support rail.
 The broken lines depict portions of the support rail that form no part of the claimed design.
